Primary Examiner — Gino Colan(74) *Attorney, Agent, or Firm* — Brinks Gilson & Lione(57) **CLAIM**

We claim the ornamental design for a barrow cart, as shown and described.

DESCRIPTION

FIG. 1 is a top perspective view of a barrow cart showing our new design;

FIG. 2 is a top plan view thereof;

FIG. 3 is a bottom plan view thereof;

FIG. 4 is a front elevation view thereof;

FIG. 5 is a rear elevation view thereof;

FIG. 6 is a left side elevation view thereof; and,

FIG. 7 is a right side elevation view thereof.

The broken lines in FIGS. 1-7 illustrate portions of the barrow cart that form no part of the claimed design.

1 Claim, 6 Drawing Sheets(56)
